US00D794871S

(12) **United States Design Patent** (10) Patent No.: **US D794,871 S**
Mintz et al. (45) Date of Patent: **** Aug. 15, 2017**

(54) CLIPPER	5,211,648 A	5/1993	Demeester
(71) Applicant: Medline Industries, Inc. , Northfield, IL (US)	5,251,375 A	10/1993	Crucq
	D342,345 S	12/1993	Yonezawa
	5,306,285 A	4/1994	Miller
	5,325,589 A	7/1994	Kubo
	5,367,599 A	11/1994	Okada
(72) Inventors: Stuart Mintz , Glenview, IL (US); Robert Lockwood , Libertyville, IL (US)	5,413,358 A	5/1995	Austin, Jr.
	5,484,434 A	1/1996	Cartmell
	5,512,721 A	4/1996	Young
	5,544,415 A	8/1996	Huang
	5,550,452 A	8/1996	Shirai
(73) Assignee: Medline Industries, Inc. , Northfield, IL (US)	5,557,850 A	9/1996	Mun
	5,579,581 A	12/1996	Melton
	5,600,890 A	2/1997	Leitner
	5,606,799 A	3/1997	Melton
	5,715,601 A	2/1998	Nakatani
	5,801,637 A	9/1998	Lomholt
	5,802,932 A	9/1998	Vankov
	5,835,455 A	11/1998	Hanson
(21) Appl. No.: 29/551,693	5,920,988 A	7/1999	Momose
(22) Filed: Jan. 15, 2016	5,925,002 A	7/1999	Wollman
(51) LOC (10) Cl. 28-03	5,933,964 A	8/1999	Altamore
(52) U.S. Cl. USPC D28/53	5,937,526 A	8/1999	Wahl
(58) Field of Classification Search USPC D28/49-54	5,970,616 A	10/1999	Wahl
CPC B26B 19/00-19/12; B26B 19/20-19/36; B26B 19/38-19/3886	5,973,497 A	10/1999	Bergk

(57) CLAIM

We claim the ornamental design for a clipper, as shown and described.

DESCRIPTION

The patent or application file contains at least one drawing executed in color. Copies of this patent or patent application

publication with color drawing(s) will be provided by the Office upon request and payment of the necessary fee. FIG. 1 is a perspective view showing a first embodiment of our new design of a clipper having a blue front portion and orange side portions, where the blue front portion is indicated with horizontal lines and the orange side portions are indicated with cross-hatching; FIG. 2 is a top plan view thereof; FIG. 3 is a right side elevational view thereof; FIG. 4 is a front elevational view thereof; FIG. 5 is a left side elevational view thereof; FIG. 6 is a rear elevational view thereof; FIG. 7 is a bottom plan view thereof; FIG. 8 is a perspective view showing a second embodiment of our new design of a clipper having a blue front portion and orange side portions, where the horizontal lines indicate blue color of Pantone 286C or Pantone 287C, and the cross-hatching indicates orange color of Pantone 1655C or Pantone 021C;

FIG. 9 is a top plan view thereof; FIG. 10 is a right side elevational view thereof; FIG. 11 is a front elevational view thereof; FIG. 12 is a left side elevational view thereof; FIG. 13 is a rear elevational view thereof; FIG. 14 is a bottom plan view thereof; FIG. 15 is a perspective view showing a third embodiment of our new design of a clipper with a blue front portion and orange side portions; FIG. 16 is a top plan view thereof; FIG. 17 is a right side elevational view thereof; FIG. 18 is a front elevational view thereof; FIG. 19 is a left side elevational view thereof; FIG. 20 is a rear elevational view thereof; and, FIG. 21 is a bottom plan view thereof.
